(57) **CLAIM**

The ornamental design for a portable seat, as shown and described.

DESCRIPTION

FIG. 1 is a top, front, left side perspective view of a portable seat showing our new design in an open configuration.

FIG. 2 is a bottom, rear, right side perspective view of the portable seat illustrated in FIG. 1 in the open configuration. FIG. 3 is a front elevation view of the portable seat illustrated in FIG. 1 in the open configuration.

FIG. 4 is a left side elevation view of the portable seat illustrated in FIG. 1 in the open configuration.

FIG. 5 is a top plan view of the portable seat illustrated in FIG. 1 in the open configuration.

FIG. 6 is a right side elevation view of the portable seat illustrated in FIG. 1 in the open configuration.

FIG. 7 is a rear elevation view of the portable seat illustrated in FIG. 1 in the open configuration.

FIG. 8 is a bottom plan view of the portable seat illustrated in FIG. 1 in the open configuration.

FIG. 9 is a top, front, left side perspective view of the portable seat illustrated in FIG. 1 showing our new design in a closed configuration.

FIG. 10 is a bottom, rear, right side perspective view of the portable seat illustrated in FIG. 9 in the closed configuration.

FIG. 11 is a front elevation view of the portable seat illustrated in FIG. 9 in the closed configuration.

FIG. 12 is a left side elevation view of the portable seat illustrated in FIG. 9 in the closed configuration.

FIG. 13 is a top plan view of the portable seat illustrated in FIG. 9 in the closed configuration.

FIG. 14 is a right side elevation view of the portable seat illustrated in FIG. 9 in the closed configuration.

FIG. 15 is a rear elevation view of the portable seat illustrated in FIG. 9 in the closed configuration; and,

FIG. 16 is a bottom plan view of the portable seat illustrated in FIG. 9 in the closed configuration.

(Continued)

The dashed broken lines in the figures represent portions of the portable seat that form no part of the claimed design.
